UNITED STATES PATENT OFFICE

2,642,512

MERCURY OR LIQUID CONTACT SWITCH

Israel Shamah, New York, N. Y., assignor to
Ismah Corporation of New York

Application January 5, 1951, Serial No. 204,505

5 Claims. (Cl. 200—152)

1

This invention relates to mercury or liquid contact switches.

It is an object of the present invention to provide a mercury switch wherein there is incorporated within the switch a circuit-breaking feature so that upon overload of a circuit including this switch, the mercury is forcibly displaced from its position between contacts to a position removed therefrom and retained thereat until the switch is again tilted to its set position.

It is another object of the invention to provide a mercury switch having a chamber which is lined with porcelain to render the switch free from injury resulting from an electrical discharge and to make unnecessary the delicate operations usually provided with mercury switches on filling such switches with hydrogen gas and thereby to provide such a switch wherein hydrogen is unnecessary and which provides a structure that permits easy filling with hydrogen should the need for the hydrogen seem needed.

It is another object of the invention to provide a simple construction and method of assembly of the parts of a mercury switch wherein the contact terminals are extended into the mercury chamber through a covering element forming one end of the ceramic enclosure and wherein the sealing of the unit is effected over the terminals to hold them in place and to close off and insulate the end of the mercury switch element.

It is another object of the invention to provide a mercury switch element whereby the mercury chamber is set within the handle and forms an integral part thereof.

It is still another object of the invention to provide a mercury switch element wherein contacts are provided on the end of the mercury element and wherein these contacts slide over arcuate fixed or stationary contacts to which the switch wires are connected and thereby to simplify the arrangement of contacts for mercury switches.

It is still another object of the present invention to provide a mercury switch element which lends itself for multiple gang operation and has a securing element to connect the same for operation in unison with a shaft along with other mercury elements and wherein the fixed contacts for the individual elements are disposed above and below the elements out of the way and so as not to give interference with the operation of other mercury elements.

Other objects of the invention are to provide

2

in mercury switches that are of simple construction, easy to assemble, inexpensive to manufacture, compact, has a minimum number of parts, capable of carrying a heavy load, fireproof, and efficient in operation.

For other objects and for a better understanding of the invention, reference may be had to the following detailed description taken in connection with the accompanying drawing, in which:

Fig. 1 is a perspective view of the mercury switch bearing the mercury element constructed according to one form of the present invention.

Fig. 2 is a vertical sectional view of the switch taken on line 2—2 of Fig. 1.

Fig. 3 is a side elevational view of the switch of Fig. 1 with portions broken away to show the mercury element and with the switch handle elevated to the on position.

Fig. 4 is an exploded perspective view of the switch assembly shown in Fig. 1.

Fig. 5 is a fragmentary transverse sectional view of the mercury element taken on line 5—5 of Fig. 4.

Fig. 6 is a fragmentary side elevational view of a switch assembly employing a switch element adapted to be placed in three positions and wherein upon overload, the mercury is displaced and retained in a removed position within the element automatically to break the circuit.

Fig. 7 is a perspective view of the mercury switch fuse element and its operating handle as used in the form of the invention shown in Fig. 6.

Fig. 8 is a fragmentary longitudinal sectional view of the switch fuse element shown in Fig. 7, as viewed on line 8—8 thereof.

Fig. 9 is a longitudinal sectional view of the switch fuse element shown in Fig. 6, and similar to Fig. 8 but elevated to the "on" position to deposit the mercury over the switch contacts.

Fig. 10 is an enlarged transverse sectional view taken on line 10—10 of Fig. 8 with the switch element being in the "off" position.

Fig. 11 is an enlarged transverse sectional view of the switch element in the "on" position and as viewed on line 11—11 of Fig. 9.

Fig. 12 is an exploded perspective view of the switch fuse element shown in Fig. 6.

Fig. 13 is a perspective view of a modified form of the invention with portions broken away to show the interior construction of the switch and wherein the contacts of the switch element are provided on the end thereof and are slidable over arcuate contacts fitted in the housing.

Fig. 14 is a perspective view of the switch fuse element used in the form of the invention shown in Fig. 13.

Fig. 15 is a perspective view of the switch housing used with the form of the invention shown in Fig. 13.

Fig. 16 is a perspective view of a multiple button switch assembly with switch fuse elements arranged in gang fashion.

Fig. 17 is an enlarged side elevational view of one of the switch fuse elements used in the multiple unit switch assembly shown in Fig. 16 with portions of the same broken away to show the interior construction thereof and to show an adjusting screw for fixing the element to the gang shaft.

Fig. 18 is a perspective view of a mercury switch having pig-tail wires and without intervening friction contact parts.

Referring now particularly to Figs. 1 to 5, 21 represents a casing having a large recess 22 in which mercury switch element 23 is connected for tilting adjustment. The ends of the casing 21 are enlarged and are cut away respectively at 24 and 25 to receive respectively contacts 26 and 27. The contact 26 fits in the recess 24 and a wire can be connected thereto by screw 28. This screw 28 may enter hole 29 in the enlarged end of the casing 21.

The contact member 27 fits the recess 25 and will be projected along the opposite side of the casing 21. This contact strip 27 is held in place by a screw 30 to which a wire can be attached and this screw enters a hole 31 in the recess 25. The respective contact strips 26 and 27 have 35 depressed ends 32 and 33 respectively adapted to seat in depressions 34 and 35 respectively of contact strips 36 and 37 on the mercury switch element 23.

The switch element 23 has an opening or chamber 38 therein that is lined with ceramic material 39, such as porcelain, in the form of an open ended box slidable into the opening 38 in the body of the element when being assembled. The contact strips 36 and 37 extend along the opposite sides of the switch element body, preferably in grooves therein and their respective ends are bent around the end of the body and projected into the opening 38 and into the ceramic vessel 39 in spaced relationship, as indicated at 41 and 42. A ceramic plate 43 has holes therein for receiving the ends 41 and 42 in such a manner as to hold these ends in relationship relative to one another. The contacts 36 and 37 have the ceramic plate 43 and are made fixed by adding self-hardening cementitious material, as indicated at 44, such as a cold setting phenolic, porcelain paste, or a bituminous sealer. The material should withstand the stresses and strains of heat. If desired, the entire assembly can be of molded construction with the porcelain parts either molded in or dispensed with, depending upon the load of the circuit with which the switch is to be used.

The switch element body 23 has an integral handle portion 45 with side shoulder formations 46 thereon engageable with spring wire portions 47 on a mounting plate 48 which is secured to the front of the casing member 21 by attaching screws 49 and 50. The shoulder formations 46 respectively have sides angled with respect to one another and each side can fit in an intermediate portion 51 of the spring wire retaining members 47, Fig. 4. By this spring wire retaining member and the seating of the sides of the

shoulder formation 46 therein, the switch element will be retained in either its "off" position, as shown in Fig. 2, or in its "on" position, as shown in Fig. 3.

The chamber 38 has a deposit of mercury 52 therein. When the switch is in the "off" position, as shown in Fig. 2, this mercury will be deposited in the forward end of the ceramic vessel 39, but upon the switch element being pivoted to the "on" position, as shown in Fig. 3, the mercury deposit 52 will lie in the rear end of the vessel 39 and will bridge the contact portions 41 and 42 to establish an electric circuit therebetween. The entire assembly, by means of the mounting plate 48 can be fixed as a unit in the usual wall outlet or receptacle.

Referring now particularly to Figs. 6 to 12, there is shown a modified form of the invention wherein the switch element serves as a fuse for the electric circuit governed by the switch. According to this form of the invention, 55 represents the switch element. This switch element has a hollow portion 56 and an integral handle portion 57.

This hollow portion 56 provides for an opening 58 in which is disposed a specially formed ceramic box having a bottom part 59 providing an abutment 60 and an inclined pocket 61 into which mercury 62 can be collected. On this same part 59 is a recess 63 with a central barrier 64. Into this recess there is extended inwardly bent ends of contacts 65 and 66 for engagement with a mercury body. Mercury may lie on the opposite side of the barrier 64 and over the contact ends without establishing a circuit between the contact ends. With the switch element 55 tilted to provide the mercury in the end of the space 58 and over the barrier a circuit will be established. This barrier has its edge depressed at its rear end so as to permit the mercury to pass thereover and the low point on this edge is below the abutment 60. A top part 67 of the ceramic vessel is disposed over the part 59, Fig. 8. Upon an overload being effected through the switch circuit, the mercury will be blown over the abutment 60 and will be collected in the pocket 61. The mercury will be lowered below the low point in the edge of the barrier 64. Because of the provision of the ceramic parts, it is unnecessary to use hydrogen in the switch element and the switch element will be protected against excess heat tending, when it occurs, to fuse the walls of the opening were it not for the provision of the ceramic parts. If hydrogen is to be disposed within the chamber, it can be done very nicely by injection by a needle through a self-sealing sealer which will automatically seal off the chamber as the needle is withdrawn.

On the ends of the ceramic parts there is disposed a closure plate 68 under which the bent ends of the terminals or contacts extend. Self-hardening cementitious material, as indicated at 69, is formed over the closure plate 68 and over 65 the terminal ends whereby to hold the plate 68 and the contact terminals 65 and 66 in place.

As shown in Fig. 12, the barrier 64 is fitted into a recess 70 in the abutment 60 and projects rearwardly beyond the bottom part 59 of the box. The closure plate 68 has a bottom slot 71 adapted to receive the rear end of the barrier 64 whereby to hold the barrier 64 against lateral displacement.

The outer surface of the hollow portion 56 of the switch element 55 is provided with grooves

receiving respectively portions of the contact terminals 65 and 66. Each of these terminals have an upstanding portion 72 which extends onto the side of the hollow portion 56 to provide a bearing 73 for engagement with respectively contact strips 26 and 27 adapted to lie in the casing 21 and be secured by screws 28 and 30 respectively.

On mounting plate 48, Fig. 6, there is provided parallel spring wires 74 having respectively depressions 75, 76 and 77 therein for receiving pointed shoulder formations 78.

With the switch element being moved to the tilted down position, as shown in full in Fig. 6, mercury 62 will lie in the pocket 61 and the switch will be in the "off" position. If the handle 57 is lifted to locate the shoulder 78 in the depression 75, the mercury will be transferred to the recess 63 and the switch will be turned on and upon thereafter bringing the pointed flange 78 to the depression 76 in the wire 74, the switch element will be set so that the mercury can be spilled over the shoulder 60 upon an overload current passing through the switch and so as to break the circuit therethrough and to lower the mercury to a point below the upper edge of the barrier 64. To again establish the circuit in the switch the handle element is moved to the "on" position, as shown in Fig. 6, and then returned to the set "on" position. When the switch is lowered to the full line position shown in Fig. 6, the circuit controlled by the switch will be broken.

Referring now particularly to Figs. 13, 14 and 15, 80 represents a casing which is open at its front end and has vertically-spaced bosses 81 and 82 with threaded openings for receiving screws 84 and 85 respectively that secure a mounting plate 86 thereon. The rear wall of the casing is of arcuate shape, as indicated at 87, and has laterally spaced radially inwardly extending guide portions 88 and 89. Between these guide portions there are disposed arcuate shaped contact strips 90 and 91 that extend downwardly and forwardly and then downwardly through opening 92 for connection with wires 93 and 94 respectively. A depending boss 95 receives screws 96 and 97 which hold the contact terminal strips 90 and 91 in place within the casing 80.

A mercury switch fuse element 98 is adjustable within the casing 80 and has a handle portion 99 which extends outwardly through the opening in the mounting plate 86. This element has shoulder portions 100 and 101 on the opposite sides of the same bearing against spring wire 102 recessed to receive the shoulders and disposed on the rear face of the mounting plate 86. On the opposite end of the element 98 are contacts 103 and 104 engageable respectively with the contact terminals 90 and 91.

The contact ends 103 and 104 are rounded so as to have smooth travel over the arcuate contact strips 90 and 91. This construction makes unnecessary the long contact terminal strips on the body of the element 98 and also eliminates the need for grooves thereover.

Referring now particularly to Figs. 16 and 17, there is shown a form of the invention wherein the elements are adapted for operating in gang fashion or individually. According to this form of the invention, there is provided a casing 110 having an open forward end over which is fixed a plate 111 having a plurality of spaced holes 112 therein. This plate is secured to the casing

110 by screws 113 disposed respectively in corner openings 114 thereof. Extending through the rear of the casing are spring contacts 115 and 116 which are respectively made secure on the rear part of the casing by screws 117 which also serve to fix wires 118 respectively to these contacts. These contacts are arranged in pairs and are vertically-spaced from one another.

Mercury switch fuse elements 119 are constructed as shown in Fig. 17 and are respectively connected to a shaft 120 extending laterally from one side of the casing to the other. These elements have a depending boss 121 through which the shaft 120 extends. A securing screw 122 is carried by this boss and can be connected to the shaft 120 so that the shaft can be rotated upon moving one of the elements 119 and simultaneously the other elements will be moved or, if desired, the elements can be mounted for independent rotation on the shaft so that a selective use of the switch elements is had. Each of the elements 119 have a handle portion 123 which extends outwardly from the front plate 111.

The element 119 is hollow and is provided with ceramic parts to overcome the rupture of the element upon overload occurring. These ceramic parts provide a shoulder 124 and an inclined surface 125 forming the bottom of a pocket for receiving the mercury upon overload being effected. Contacts 126 and 127 run out of the rear end of the element respectively over the bottom end faces of the elements and have respectively stop formations 128 for receiving respectively bent ends 129 of the respective contact strips 115 and 116 to retain the element 119 in either of its adjusted positions.

A barrier 130 has a depressed edge over which mercury 131 may pass to establish the circuit between the contacts 126 and 127.

Referring now particularly to Fig. 18, there is shown an element 133 constructed generally along the lines of the element 23 of Fig. 4 and of element 98 of Fig. 14. This element will have the usual integral handle 134 and instead of having strip contacts extending from the end of the same, pig-tail wires 135 and 136 are embedded in the sealing material indicated at 137 and they have respectively terminal elements 138. These pig-tail wires permit the use of the element without the need for intervening friction contact parts.

It will now be seen that there has been provided a mercury switch construction wherein the mercury opening is provided in a body to which the handle is integrally connected and wherein the opening within the body is lined with porcelain which is adapted to withstand heavy heat resulting from an overload in the circuit and wherein the end part of the porcelain and the terminals, which are extended thereinto in order to have contact with the mercury, are connected and held fixed on the end of the body by a self-hardening composition.

It will also be apparent that there has been provided a simple mercury switch fuse element wherein the lining parts within the element body provide a chamber and one of these parts is so formed as to provide an abutment separating two pockets between which the mercury can be transferred and where there is provided in one of the pockets a longitudinally extending barrier having a lowered edge over which the mercury may extend when the switch body is in the "on" posi-

tion to establish a liquid contact between the terminals extended thereinto.

It will also be apparent that a switch element constructed according to the present invention can be readily adapted for use in gang formation and which consumes little space even when used with one another. It will also be seen there has been provided simple means for making contact with the terminals of the mercury element through the switch casing parts.

While various changes may be made in the detail construction, it shall be understood that such changes shall be within the spirit and scope of the present invention as defined by the appended claims.

What is claimed is:

1. A mercury switch element comprising an insulating body having an elongated opening therein, a ceramic structure provided in the opening to protect the walls of the opening from high heat which may be generated by the mercury on an overload occurring, said ceramic structure including an end part, terminal strips extending through the end ceramic part and adapted to be bridged by mercury within the opening and self-hardening material extending over the end part and fixing the same and the terminals to the switch element body, said terminals being bent to extend in spaced relation over the edge of the body, and having respectively hook formations at the ends for receiving stationary terminals and to retain the switch body in its adjusted positions, and said ceramic structure having pocket openings for the collection of mercury in the opposite ends thereof with an abutment lying between them whereby the mercury can be effectively restrained in either end of the body opening.

2. A mercury switch element as defined in claim 1 and a longitudinally-extending barrier lying in one of the pockets intermediate the sides thereof and connected between the abutment and the end part and having a low edge portion over which mercury may extend to provide the liquid contact between the terminals and upon the switch element being tilted to position the mercury in the one terminal pocket.

3. A mercury switch element as defined in claim 1 and a longitudinally-extending barrier lying in one of the pockets intermediate the

10 sides thereof and connected between the abutment and the end part and having a low edge portion over which mercury may extend to provide the liquid contact between the terminals and upon the switch element being tilted to position the mercury in the one terminal pocket and said abutment having a slot receiving one end of the barrier and said end part having a slot receiving and retaining the opposite end of the barrier.

4. A mercury switch element as defined in claim 1 and a longitudinally-extending barrier lying in one of the pockets intermediate the sides thereof and connected between the abutment and the end part and having a low edge portion over which mercury may extend to provide the liquid contact between the terminals and upon the switch element being tilted to position the mercury in the one terminal pocket, said 15 switch body having a laterally-extending opening to serve for the mounting of the switch element upon the shaft and a securing element within the body for securing the body to a shaft lying within the opening.

20 5. A mercury switch element comprising an insulating body having an elongated opening therein, a ceramic structure provided in the opening to protect the walls of the opening from high heat which may be generated by the mercury on an overload occurring, said ceramic structure including an end part, terminal strips extending through the end ceramic part and adapted to be bridged by mercury within the opening and self-hardening material extending 25 over the end part and fixing the same and the terminals to the switch element body, said terminals being bent to extend over the upper and lower edges respectively of the body and having respectively hook formations at the ends for receiving stationary terminals and to retain the switch body in its adjusted positions.
